HOWARD L. SHUTTLEWORTH, OF AMSTERDAM, NEW YORK, ASSIGNOR TO MOHAWK CARPET MILLS, INC., OF AMSTERDAM, NEW YORK, A CORPORATION OF NEW YORK

TUFT CUTTING MECHANISM

Application filed March 17, 1932. Serial No. 599,388.

This invention relates to looms for weaving pile fabrics, such as those of the Axminster type, and is concerned more particularly with a novel mechanism to be used in such looms for cutting the yarns forming the pile tufts.

Looms for weaving tufted pile fabrics by operations which involve inserting the tufts in rows across the fabric include means for cutting or shearing the pile yarns from their sources of supply, and the cutting devices now commonly employed are of two types. One form of cutting mechanism severs the yarns before they are inserted between the warp threads of the fabric, while the other form functions after the yarns have been inserted and bound in place. Both forms of cutting mechanism are open to serious objections, and interfere to a considerable extent with increasing the speed of production of the loom.

In looms in which the pile yarns are cut after they have been inserted in the fabric, the cutting device usually includes inner and outer cutting blades mounted on bars extending across the loom and lying on opposite sides of the inserted row of tufts. At the proper instants in the operation of the loom, these bars are moved toward each other by suitable means, such as cams and levers, and the knives cooperate to shear the yarns. In order that the knives may cut properly, they must bear against each other with substantial pressure, and unless the bars are strong and of heavy rigid construction, there is a danger, particularly in wide looms, that the bars will spring or bend, and thereby impair the cutting action. Devices of this type consume a substantial amount of power both in the movement of the bars and in the actual cutting action, and the movement back and forth of these large masses, particularly in wide looms, causes excessive vibration, reduces the smoothness of operation, and prevents operating the loom at high speeds. Also, the cutter blades have to be removed from the loom from time to time to be resharpened, and this represents a loss in time and productivity of the loom.

In looms in which the pile yarns are severed before the tufts are inserted, tuft grip-

pers draw the yarns between the teeth of a comb during each cycle of loom operation, and the yarns are then cut by one or more long stroke cutting knives which are traversed along the face of the comb. The operations incidental to the cutting of the yarns in this manner, and especially the movement of the knives, consume a considerable proportion of each loom cycle and the operation of the loom is correspondingly slowed down. In addition, such cutting devices require complicated and bulky actuating mechanism consuming a substantial amount of power, and the entire cutting mechanism seriously interferes with speeding up the loom to increase its output.

The present invention is accordingly directed to the provision of new cutting mechanism for the purpose referred to, which is an improvement over those heretofore used, in that it is simpler and of lighter weight, may be operated at higher speeds, functions without undue vibration, permits the production of fabrics of shorter tuft length, and is cheaper and easier to maintain in proper operating condition.

The new mechanism includes a plurality of small cutting blades removably mounted in holders in an endless traveling member, such as a chain driven by suitable driving means. The traveling member is carried on a movable support which lies at one side of the row of inserted tufts, and on the other side of the row is a back member which provides support to the yarns during the cutting operation. The movable support and the back member, both of which are of relatively light weight, are caused to approach and recede from one another by suitable means, and at the proper instants in the operation of the loom and upon the insertion of each row of tufts, the support and back member advance toward the yarns, and the knives on the traveling member sever the yarns while they are engaged and supported by the back member. The support and back member are then retracted and the operation of the loom proceeds.

Since the new mechanism is of relatively light weight, and the cutting operation is

performed by it in a very short period of time, it can be actuated at high speeds. Also, it functions without substantial vibration and the mechanism severs the tufts evenly and 5 can be adjusted to produce much shorter tufts than is possible with the devices now used. The knives employed are preferably of the wafer type, resembling razor blades, and as the dull knives may be quickly removed from their holders, and new ones as 10 quickly inserted, the loss in productive loom time caused by the maintenance of the cutting mechanism is materially reduced.

For a better understanding of the invention, reference may be had to the accompanying drawings, in which

Fig. 1 is a view in side elevation of an Axminster loom embodying the invention;

Fig. 2 is an enlarged sectional view of the cutting mechanism showing the parts in position to cut the yarns;

Fig. 3 is a view of the cutting mechanism in front elevation;

Fig. 4 is a plan view of the cutting mechanism shown in Fig. 3;

Fig. 5 is a fragmentary sectional view showing a detail of the cutting mechanism;

Fig. 6 is a longitudinal sectional view of a portion of the cutting mechanism;

Fig. 7 is an end view of a knife holder, and

Fig. 8 is a side view of a portion of a knife holder.

In the drawings, there is conventionally illustrated a loom 10 provided with transporting chains 11 on which tube frames 12 are carried, the frames being advanced successively to a point above the weaving devices where a transfer mechanism which includes a pair of arms 12' picks up each frame and 35 lowers it to insert the ends of the yarns wound on the spool in the frame between the warp threads of the fabric. Upon insertion of the yarns, a shot of weft is introduced into the fabric, the ends of the yarns are 40 looped about the weft shot in the usual way, and the yarns are severed between the fabric and the spool to produce tufts of the proper 45 length.

The new mechanism used for severing the 50 yarns comprises a bar 13 attached by means of brackets 14 to the ends of arms 15 fast on shaft 16 journaled in bearings on the loom side frames 17. Mounted on the shaft 16 is an arm 18 to which is attached one end of a 55 spring 19, the other end of which is secured to a bracket 20 attached to any suitable part of the loom. The spring acting through arm 18 tends to rock the shaft to swing the arms 15 in a counter-clockwise direction, this 60 movement being limited by means of a stop 21 against which the arms 15 normally bear. The shaft 16 and arms 15 are rocked clockwise by means of an arm 22, also fast on shaft 16, which is attached by a link 23 to one arm 24 65 of a bell crank pivotally mounted in bear-

ings in a bracket 25 attached to a suitable part of the frame of the loom. The other arm 26 of the bell crank carries a roller 27 at its end which is engaged by a cam 28 mounted on the cam shaft 29 of the loom. 70 As the cam rotates during the operation of the loom, the cam acts through the bell crank and the connections described to cause arms 15 to advance the cutting mechanism to operative position, this action being timed to 75 occur after the tufts are formed.

The pile yarns wound on the spool in a tube frame pass out through guide tubes 30 on the frame and when the ends of the yarns are inserted between the warp threads and a 80 shot of weft is introduced into the fabric, the yarns are held at one point by the shot of weft and extend backwardly from that point through the tubes to the spool. When the cutting mechanism now moves into contact with the yarns, some support for the 85 yarns on the side opposite to that from which the cutting mechanism approaches is desirable, so that the cut will be clean rather than ragged. This support may best be afforded to the yarns just above the point of cutting and such support also serves to keep the cut ends in line with the guide tubes so that the 90 ends are straight for the next insertion of the yarn in the warp.

The back support or guide in the new mechanism takes the form of a plate 31 of suitable light material mounted to reciprocate in slots 32 in brackets 33 attached to the loom frame. In a loom in which movable shearing knives have been used, the back support may be mounted in the usual back knife slides and operated by the mechanism employed for reciprocating that knife. This mechanism includes pins 34 on the back support, each pin being connected by a rod 35 to one arm 36 of a bell crank pivotally mounted at 37, the other arm 38 of the bell crank carrying a roller 39 which is acted upon by a cam 40 on the cam shaft of the loom. Each bell crank is normally held against a stop 41 by a spring 42 attached at one end to the bell crank and at the other to a suitable part of the loom side frame, and the cam 40 is so formed that at the proper instant in the operation of the loom when the cutting of the tuft yarns is to be performed, the bell cranks are rocked, advancing the back support 31 so that its forward end engages the yarns.

The bar 13 of the cutting mechanism is 120 provided at one end with a bearing 43 for a shaft 44 which carries a sprocket wheel 45 and at the other end of the bar with a bearing 46 for a shaft 47 carrying a sprocket wheel 48. The shaft 47 extends through its bearing and on its exposed end carries a bevel gear 49 meshing with a gear 50 on the end of shaft 51 journaled in bearing 52, the shaft being driven by any suitable means, such as 125 a flexible shaft 53, which shaft may be con- 130

nected to the driving means for the loom or to a separate driving means, such as an electric motor. A chain 54 is led around sprocket wheels 45 and 48 and knife holders 55 are mounted on this chain at suitable intervals. Each knife holder has a portion 56 offset from the plane of the chain and extending outward beyond the chain a substantial distance, the offset portion terminating in an end portion 57 which extends at an angle to the plane of the chain. The end portion has a slot 58 in its edge and in this slot is mounted a knife blade 59 of generally triangular shape. The ends of the slot are undercut (Fig. 8) and the blade has a projection 60 extending outward from its base at one end, the proportions of the parts being such that the knife may be inserted freely in the slot and then moved endwise so that the projection 60 lies under an overhanging portion at one end of the slot and the pointed end of the knife lies under an overhanging portion at the other end of the slot. In normal operation, the movement of the chain is such that the knives tend to be forced by contact with the yarns into the locking position shown in Fig. 8 and cannot escape from their holders.

To maintain the chain taut, the bar 13 is provided at each end with adjustable bearings 61, 62 attached to the bar by bolts 63 which pass through slots in the bar. In each of the bearings 61 and 62 are shafts 64 carrying idler sprocket wheels 65 which bear against the chain and may be adjusted to keep it as taut as desired. Since the knives should move in a straight line during the cutting operation and thus cut the tufts at a uniform height, the bottom portion of the chain which carries those knives which take part in the actual cutting operation is guided so that it will not sag, and for this purpose a bar 66 is attached to the angle portion 67 of bar 13, the bar 66 having a portion 68 which underlies the lower stretch of the chain and terminates in an upstanding flange 69, the upper surface of which is machined and provides a support for the chain. Means are provided for maintaining the chain in close contact with the surface of flange 69, the means including a channeled bar 70 detachably connected to bar 66 and lying above the chain with the channel facing the chain. In the channel is disposed a vertically movable bar 71 which bears against the chain and is forced into contact therewith by leaf springs 72 secured in the bottom of the channel and bearing against the upper surface of bar 71. With this arrangement, the lower stretch of the chain which carries the knives which perform the cutting action at any instant is supported on the machined surface of flange 69 and is held in contact with that surface by the bar 71 resiliently forced against the chain.

In the operation of the device, the arms 15 which may constitute the front knife sup-

ports of an ordinary tuft shearing mechanism are swung to advance the new cutting mechanism toward the yarns which are to be cut. At the same time, the back support 31 is advanced so that its forward edge engages the yarn above the points where the cutting is to take place. The chain on which the knife blades are mounted always runs in the same direction and with either a continuous or intermittent movement. As the cutting mechanism approaches the yarns, the blades in the holders on the lower stretch of the chain eventually come into contact with and sever the yarn ends. Since the blade holders 57 are inclined at an angle to the plane of movement of the chain and these holders lie at a substantial distance beyond and at one side of the chain, the knives can be brought down close to the plane of the fabric so that the pile of the fabric is very short, the new mechanism permitting the tufts to be cut much more closely than is possible with the types of cutting mechanism heretofore used.

The total weight of the cutting mechanism is much less than that of the reciprocating front knife of the shearing type of cutting mechanism and the new mechanism can, therefore, be operated at higher speeds without producing undue vibration. By reason of the manner in which the cutting blades are supported, the pile is cut uniformly across the fabric regardless of the width of the loom and no difficulties are encountered due to sagging or bending as in the case of the shearing knives. Also, the small knife blades of the present cutting mechanism can be quickly removed and replaced so that there is little or no time lost in the operation of the loom in keeping the cutting mechanism in proper condition.

I claim:

1. In a loom for weaving pile fabrics, the combination of means for inserting in the fabric pile yarns drawn from a source of supply, and means for severing said yarns between the fabric and the source of supply, said severing means comprising an endless traveling member moving continuously in one direction and knives carried thereby, said member and knives lying at one side of the group of yarns to be cut, and a support on the other side of the group of yarns for holding them while they are being cut.

2. In a loom for weaving pile fabrics, the combination of means for inserting in the fabric pile yarns drawn from a source of supply, and means for severing said yarns between the fabric and the source of supply, said severing means comprising an endless traveling member moving continuously in one direction and carrying knives, and a mounting for the member movable to bring said knives into and out of operative position relative to the yarns to be cut.

3. In a loom for weaving pile fabrics, the combination of means for inserting in the fabric pile yarns drawn from a source of supply, and means for severing said yarns between the fabric and the source of supply, said severing means comprising an endless traveling member carrying knives, said member and knives lying on one side of the group of yarns to be cut a mounting for the member, means for advancing and retracting said mounting to move the knives into and out of operative position, and a support on the other side of the group of yarns for holding them while they are being cut. 15
4. In a loom for weaving pile fabrics, the combination of means for inserting in the fabric pile yarns drawn from a source of supply, and means for severing said yarns between the fabric and the source of supply, said severing means comprising an endless traveling member moving continuously in one direction and carrying knives, and a swinging mounting for said member, said mounting moving the knives into and out of operative position. 20
5. In a loom for weaving pile fabrics, the combination of means for inserting in the fabric pile yarns drawn from a source of supply, means for severing said yarns between the fabric and the source of supply, said severing means comprising an endless traveling member moving continuously in one direction and carrying knives, said member and knives lying at one side of the group of 30

5 nation of an endless member traveling substantially in a plane, a plurality of knives mounted on said member and having cutting edges lying beyond said member, said member and knives lying at one side of the group of yarns to be cut, means for driving said member, means for shifting said member bodily to bring said knives into and out of cutting position, and a support on the other side of said group of yarns for holding them while they are being cut.

10 15 20 25 15. In a cutting mechanism for severing pile yarns drawn from a source of supply and inserted in a row into a fabric, the combination of an endless member, a plurality of knives mounted on said member and having cutting edges lying beyond said member, said member and knives lying at one side of the group of yarns to be cut, means for guiding a portion of said member in a straight line, means for driving said member, means for moving said member toward and away from said yarns to bring said knives into and out of operative position, and a support on the other side of said group of yarns for holding them while they are being cut.

30 35 40 16. In a cutting mechanism for severing pile yarns drawn from a source of supply and inserted in a row into a fabric, the combination of a mounting, an endless traveling member on said mounting, means for guiding a portion of said member in a straight line, means for driving said member continuously in one direction, a plurality of knives carried by said member and having cutting edges lying beyond said member, and means for moving said mounting to bring the knives on the guided portion of said member into and out of operative position.

45 50 55 17. In a cutting mechanism for severing pile yarns drawn from a source of supply and inserted in a row into a fabric, the combination of a bar movable laterally, an endless member mounted on said bar and having a stretch traveling lengthwise of the bar, knives carried by said member and having cutting edges lying beyond it, said member and knives lying on one side of the group of yarns to be cut, means for driving said member, means for moving said bar laterally to bring said knives into and out of cutting position, and a support on the other side of the group of yarns for holding them while they are being cut.

60 65 18. In a cutting mechanism for severing pile yarns drawn from a source of supply and inserted in a row into a fabric, the combination of an endless member, a plurality of holders attached thereto, each holder having a knife detachably mounted thereon, and means for driving said member continuously in one direction.

19. In a cutting mechanism for severing pile yarns drawn from a source of supply and inserted in a row into a fabric, the combina-

tion of an endless member, a plurality of holders attached thereto, each holder having a slotted portion, a knife detachably mounted in each slot, and held in place by overhanging portions of the wall of the slot, and means for driving said member continuously in one direction.

20. In a cutting mechanism for severing pile yarns drawn from a source of supply and inserted in a row into a fabric, the combination of a mounting, an endless chain on said mounting, means for driving said chain continuously in one direction, means for guiding a portion of said chain to move in a straight line, holders attached to the links of the chain and extending beyond said chain, a knife in each holder, said knives in the guide portion of said chain having their cutting edges in a plane, and means for moving said mounting to bring the knives in the guided portion of said chain into and out of operative position.

25 30 35 40 45 50 55 60 65 16. In a cutting mechanism for severing pile yarns drawn from a source of supply and lying in a row, the combination of a plurality of knives, a mounting for said knives, said mounting and knives lying at one side of the group of yarns to be cut, means for moving said knives along said row of yarns, a support lying at the other side of the group of yarns for holding them while they are being cut, and means for moving said mounting and support relatively to one another and into and out of operative position relative to said yarns.

In testimony whereof I affix my signature.
HOWARD L. SHUTTLEWORTH.
